DESCRIPTION

FIG. 1 is a illustrative view of a front shoe sole showing my new design in a position of use. The broken line showing of a shoe in FIG. 1 is for illustrative purposes only and forms no part of the claimed design; FIG. 2 is a left side elevational view thereof; FIG. 3 is a front elevational view thereof; FIG. 4 is a right side elevational view thereof; FIG. 5 is a rear elevational view thereof; FIG. 6 is a top plan view thereof; FIG. 7 is a bottom plan view thereof; and, FIG. 8 is a perspective view thereof.
The article of the present design is a front shoe sole which is attached to the upper part of a shoe. The design is symmetrical in respect of the corresponding opposite front shoe sole.
